UNITED STATES PATENT OFFICE.

JOHN ROY HUNT, OF INDIANAPOLIS, INDIANA.

MOVING-PICTURE-PRINTING MACHINE.

1,320,145.

Specification of Letters Patent.

Patented Oct. 28, 1919.

Application filed February 17, 1919, Serial No. 277,594.

To all whom it may concern:

Be it known that I, JOHN ROY HUNT, a citizen of the United States, and a resident of Indianapolis, county of Marion, and State of Indiana, have invented a certain new and useful Moving-Picture-Printing Machine; and I do hereby declare that the following is a full, clear, and exact description thereof, reference being had to the accompanying drawings, in which like letters refer to like parts.

The object of this invention is to print from a negative film of the usual type, a positive film of novel type, in which the pictures are not arranged in their natural sequence.

Hitherto the films have had the pictures therein arranged in their natural sequence, in other words, in the same sequence as they appear in the negative and on the screen. This invention is to print the pictures in a different sequence or relation to each other, but so that with a suitable projecting machine the pictures will appear upon the screen in their natural sequence.

There are different forms of machines having somewhat different modes of operation for carrying out this invention. The machine herein shown, to illustrate the general nature of the invention, and which is now believed to be the preferable form, prints the pictures of the different series on the positive film in succession or alternatively. Consequently the machine herein shown has a plurality of, or at least two, display apertures in front of which one negative film and one positive film passes. But the invention is not necessarily limited to such an arrangement, as pictures of the different series may be simultaneously printed with two or a plurality of apertures, instead of doing it alternately or successively. Nor is the invention limited to the use of a plurality of apertures, as one aperture may be utilized and the film be passed across it a plurality of times, printing the pictures of one series one time and of the next series another time.

As stated the printing machine herein shown has a plurality of display apertures, one aperture for each series of pictures on the film. In the new film the second picture is located several inches from the first picture, the third picture is located near the first picture, and the fourth picture following the second picture. In other words the

pictures of the two series, either the odd or even numbered series, are spaced apart on the film so that they may be projected through the plurality of apertures in the projecting machine alternately, yet in natural sequence, the first picture being projected through one aperture, and after that the other picture through the other aperture, and after that the other picture through the first aperture, and so on. While the pictures are projected through the apertures alternately yet consecutively, they are in such order on the film that they will appear in their natural sequence on the screen. The object of this invention is to print such novel type of picture film.

A "section" of a film as used in this specification means that portion of the film which contains one picture or one blank. It is used in connection with the feeding apparatus which feeds the films two sections at a step.

In the drawings Figure 1 is an elevation of the printing machine with parts removed or broken away to display the mechanism. Fig. 2 is a central vertical section on line 2-2 of Fig. 1, some parts being broken away. Fig. 3 is a detail view of the upper cam actuated feed mechanism on an enlarged scale. Fig. 4 is a central vertical section through Fig. 3. Fig. 5 shows the lower feed mechanism with the cam operated to a different position. Fig. 6 is a section on the line 6-6 of Fig. 5. Fig. 7 is a plan view of a portion of the printed film. Fig. 8 is a vertical section of the aperture plate and the two-films in their position at the time when the first picture has been moved to printing position. Fig. 9 is the same at the time the second picture is moved to printing position and while the twenty-first picture is being printed. Fig. 10 is the same at the time the second picture is being printed and the twenty-third picture is moved to printing position.

There is shown herein a machine for printing positive films from negatives. It consists of a frame 20 with a motor 21 at the lower end geared to a vertical shaft 22 that extends entirely through the machine and drives the various parts thereof. At various stages on it there are worms 23 which mesh with worms on the parts to be driven as hereafter explained. There is a large casing 24 upon the frame 20, and upon the large casing there is secured a bar 25

which carries two spools 26 and 27 retarded by springs 28 bearing on the pin or rod 29. The upper spool 26 carries the blank film 30, upon which are to be printed the pictures from the negative film 31, which is carried on the spool 27, as shown in Fig. 2. The negative film 31 has on it the pictures in their natural sequence. The two films 30 and 31 are fed in together with the blank film 30 on the right hand or outside, as shown in Fig. 2. The pair of films are passed over feed sprockets 32, and a tension roller of the usual construction is associated with it. The two films then pass between the aperture plate 35, and pressure gate 43 and in front of the upper aperture 36 and lower aperture 37. As the films pass said apertures they are printed as hereafter explained, and then the two films pass over the lower feed sprocket 32, and the positive film then is wound upon a spool 38 carried on a triangular frame 39, and the negative film is wound upon a spool 40 carried upon said frame.

On the rear of the casing 24 there is a lamp 41 behind the upper aperture 36 and a lamp 42 behind the lower aperture 37.

In front of said apertures there are pressure gates 43 which are of usual construction pivoted at 44 which carry a small frame 45 in which is mounted a presser roller that presses against the films and holds them tight together as they pass over the aperture, and while being printed.

The feed sprockets 32 are driven by shafts 47 suitably geared thereto, and having a worm 48 meshing with the worm 23 on the shaft 22. In the machine shown herein these feed rollers are so driven as to feed the films downwardly in front of the apertures. Behind each aperture a semicircular shutter 50 is mounted upon a shaft 51, which is driven by a worm 52 meshing with the worm 23 on the shaft 22. These shutters are so geared with relation to each other that one shutter will be closed while the other is open, white printing takes place through both apertures and occurs alternately through them.

Special film feed mechanisms are provided for feeding the films intermittently through the machine so that the pictures will be printed in different sequence from the natural sequence on the negative.

The nature of the printed film and the general operation of the machine for printing it will now be explained. By referring to the more or less diagrammatical Figs. 8, 9 and 10, it is seen that the two films travel together in front of the apertures in the aperture plate, downwardly. In Fig. 8 their position is shown when picture No. 1 has been moved to printing position. The preceding part of the films are blank, or leaders, in that figure. In other words, as the films

travel downward, when picture No. 1 of the negative assumes its place in front of the aperture, said picture will be printed on the positive film 30. The leaders or advanced portion of the machine have been fed through the machine to the spool below so as to leave slack between the two apertures 36 and 37, substantially as shown. This is done continuously in feeding the films, as they are given a feeding movement first across the upper aperture and then across the lower aperture alternately. When No. 1 picture is ready to print a maximum amount of slack exists, as shown in Fig. 8. Then the films are fed two sections across the lower aperture 37, leaving a minimum amount of slack as seen in Fig. 9. Then the films are fed two sections across the upper aperture so as to bring them in position for printing picture No. 3, the intervening spaces on the printed film being left blank.

The foregoing operation is continued, alternately feeding the films two sections across first the upper and then the lower apertures until No. 2 picture is brought into printing position in front of the lower aperture 37 as in Fig. 9. When that takes place the portion of the finished printed film 39, below the second picture contains the following pictures and blanks: 1-3-5-7-9-11, that is the odd numbered pictures, which had been printed at the upper aperture, and the intervening blanks. From now on there will be no blanks printed until the odd numbered pictures run out a little before the even numbered pictures run out. Then blanks will have to take the place of omitted odd numbered pictures.

After the second picture has been printed the films are moved two sections down from the upper aperture and that brings the 23rd picture in front of the upper aperture for printing, as shown in Fig. 10. After that the films are moved two sections over the lower aperture and that brings the 4th picture in position to be printed down there. This process is repeated. Consequently there are two general series of pictures in the printed film shown here, the odd pictures and the even pictures on the negative. The odd numbered pictures are started first on the positive film and after 1-3-5-7-9-11 has been printed, the even numbered pictures then alternate with the odd numbers from that time on. While there is shown and described herein a printed film having the odd number picture up to 11 printed before the even numbered pictures start, the invention is not limited to any particular number, as there might be a difference of 5, 7 or 9 pictures between the two series. This is all determined by the amount of slack required in the machine or desired by the operator.

While in Figs. 8, 9, and 10 certain num-

bers are given to the pictures, that is only for explanation, and the numbers there given are the natural sequence numbers of the pictures on the negative film, so that one 5 can see where a certain numbered picture of the negative is located on the printed film, but in the commercial article, as produced, the pictures on the printed films are numbered thereon, as seen in Fig. 7 in short 10 repeated series for convenience. In case the film should be torn the operator could understand how to adjust his film in the projector better than if the numerals were consecutive from beginning to the end. Thus 15 the odd numbers in Fig. 7 run from 1 to 11 and the even numbered series run from 2 to 12, and then they are repeated throughout.

Referring now to the means for feeding the films through the printing machine in 20 the peculiar manner just described, there is seen in Fig. 3, secured to the inside surface of the aperture plate 35, two vertical guide bars 60 between which a feeding frame 61 vertically reciprocates. It has a cross angle bar 62 on its upper end, and another similar bar 63 at its lower end. The upper angle bar carries a horizontally slidable tooth frame 64, which has a pair of teeth adapted to project through the feed opening 65 in the 25 aperture plate, and through the feed holes 66 in the margins of the films, for feeding the films downward. The feeding tooth frame 64 carries a screw 67 which projects through a slot 68 in the angle bar 62 and carries on its lower end a roller 69 which extends into and travels along a cam groove 70 in a triangular shaped cam 71 keyed on shaft 51, as shown in Figs. 3 and 5. This cam groove is in two sections differently related to the aperture plate 35, one half of the 30 length of said groove, as shown in Fig. 4, being located far away from the aperture plate and then the other half thereof as shown in Fig. 6 being nearer said plate. 35 Therefore, as the cam revolves it moves the tooth 64 into and out of engagement with the films. While the cam is making a half revolution the teeth of the frame 64 will be in engagement with the films and will feed 40 them downward for two spaces, that is a distance equal to the width of two pictures, and then the tooth frame 64 will be withdrawn and travel upwardly again to its former upper position preparatory to another feeding movement. Since the shaft 51 45 must extend through the sliding frame 61, a vertical slot 73 is made in such frame, as seen in Figs. 3 and 5.

The construction of the lower feeding apparatus, as shown in Figs. 5 and 6, is the same as the upper one shown in Figs. 3 and 4, excepting that the two cams are geared with relation to each other that they will 50 alternately feed the films. The shutter 50 is 55 so formed and operated that it will close

each corresponding aperture at all times excepting during the printing period, and therefore, the driving means on the two shutters is so geared that they will alternately close and open the apertures and operate the special feeding means just described. Thereby, the proper relation between the shutter and feed means is established and maintained, whereby the shutter will open the aperture only when there is no feeding movement and close at all other times. 70

In maintaining and operating films as herein set forth, where the pictures are not in their natural sequence, it is necessary that 80 they be numbered or otherwise indicated so that they can be properly mounted in the projecting machine. For this operation the following mechanism is provided in connection with each of the two feeding frames 85 61 above described. On the angle bar 62 there is a finger 80 extending laterally, as shown in Figs. 3 and 5, in position to engage the push rod 81 that operates through two bars 82 secured on the aperture plate 35. 90 The rods 81 have slots 83 thereon and spiral springs 84 surrounding the rods as the feed frame recedes, and during the feeding movement, and therefore while the fingers are being moved to another printing position. 95

The rod 81 has a pin 85 that projects through a slot 86 of an arm 87 pivoted on a bearing pin 88 in the aperture plate 35. The arm 87 carries a pawl 90 adapted to engage a ratchet wheel 91 on the side of a disk 100 92 that has numerals 93 stenciled through. As shown here on the upper one of said numbering disks the numbers are 1-3-5-7- 105 9-11 and on the lower one 2-4-6-8-10-12. At each actuation of the upper disk 110 one of said numbers is brought into registration with a little shutter 94 in the aperture plate 35 just opposite the main aperture plate 37 so that said number will be printed on the margin of the film. As the feed frame 115 61 moves upward the arm 87 does not actuate the disk but leaves it stationary during the printing period.

This invention is not limited to the particular construction herein set forth, which 115 is presented for the purpose of explaining the general features of the invention.

The invention claimed is:

1. A machine for printing motion picture films, including an aperture plate having 120 therein a plurality of apertures for printing a single film, a shaft mounted at right angles to said plate within each aperture, means associated within each shaft for feeding the positive and negative films together across 125 the corresponding aperture, a shutter on each of said shafts, and means for operating said shafts in succession.

2. A machine for printing motion picture 130 films, including an aperture plate having

therein a plurality of apertures for printing a single film, a shaft mounted at right angles to said plate within each aperture, means for constantly driving said shafts for feeding 5 the positive film and the negative film together across the corresponding aperture, a shutter on each of said shafts, and means actuated by each shaft for operating said feeding means, the feeding actuating means 10 and the shutter on the different shafts being so arranged that they will give a feeding movement to the portions of the films at different apertures successively.

3. A machine for printing motion picture 15 films, including an aperture plate having therein a plurality of apertures for printing a single film, a shaft mounted at right angles to said plate within each aperture, means for constantly driving said shafts for feeding 20 the positive film and the negative film together across the corresponding aperture, a shutter on each of said shafts, a cam actuated by each of said shafts for operating the feeding means, the cams on the different 25 shafts being relatively arranged so as to cause successive operation of the feeding means for the apertures.

4. A machine for printing motion picture 30 films, including an aperture plate with a plurality of apertures in position for a single negative film and a single film on which the pictures are to be printed, a vertically slideable feeding means mounted on the inner surface of said plate within each aperture, a 35 shaft for each feeding means arranged at right angles to the plate, means for continuously driving said shafts, a cam disk secured on each of said shafts having a peripheral

groove therein, a roller extending from said feeding means into said cam groove, the 40 cam groove being so arranged as to give the feeding means its feeding movement, and the cam groove being so formed as to cause the feeding means to engage and disengage the films at the proper time, and the cams 45 on the different shafts being so arranged that they will cause successive feeding movement of the feeding means.

5. A machine for printing motion picture 50 films, including an aperture plate with a plurality of apertures in position for a single negative film and a single film on which the pictures are to be printed, a vertically slideable feeding means mounted on the inner surface of said plate within each aperture, and 55 having a pair of transversely extending bars thereon, a shaft for each plate, means arranged at right angles to the plate and between said pairs of feeding means, means for constantly driving said shafts, a cam disk 60 secured on each of said shafts between said bars and so as to engage the bars, and having a peripheral groove therein, a roller extending from said feeding means into said cam groove, the cam groove being so arranged as 65 to give the feeding means its feeding movement, and the cam groove being so formed as to cause the feeding means to engage and disengage the films at the proper time, and the cams on the different shafts being so arranged that they will cause successive feeding movement of the feeding means.

In witness whereof, I have hereunto affixed my signature.

JOHN ROY HUNT.
